UNITED STATES PATENT OFFICE.

ERNEST M. SKINNER, OF DORCHESTER, MASSACHUSETTS.

ORGAN-PIPE.

1,169,687.

Specification of Letters Patent. Patented Jan. 25, 1916.

Application filed March 26, 1915. Serial No. 17,153.

To all whom it may concern:

Be it known that I, ERNEST M. SKINNER, a citizen of the United States, and resident of Dorchester, in the county of Suffolk and 5 State of Massachusetts, have invented certain new and useful Improvements in Organ-Pipes, of which the following is a specification.

The present invention relates to organ 10 pipes and its main object is to produce a pipe which will speak with the characteristic tone of a French horn. I have accomplished this object by making certain modifications in and additions to the standard reed pipe, 15 which I will now describe and hereinafter claim.

The features in which my invention consists are illustrated in the accompanying drawings in which—

20 Figure 1 is an elevation of a reed pipe embodying my invention, the upper end of which is shown broken away. Fig. 2 is an elevation as seen from the right of Fig. 1 of the upper end of my improved organ pipe.

25 Fig. 3 is a longitudinal section on line 3—3 of Fig. 1, on an enlarged scale, representing the interior construction of the foot and shallot. Fig. 4 is a sectional view of the mouthpiece on a plane at right angles to that 30 of the line 3—3, and showing the shallot in elevation as viewed from the left of Fig. 3, the tongue and tuning wire being omitted.

Like reference characters designate the same parts in all the figures.

35 In the drawings *a* represents the foot, *b* the body, *c* the shallot or reed, *d* the tongue, and *e* the tuning wire of an organ pipe of the reed type. The foot and body are or may be constructed and connected together 40 in the manner usual with pipes of this type, being made preferably of the metal commonly used for pipe construction, although they may be made in any other metal or material whatever suitable for the purpose.

45 The foot has the usual opening *f* at one end, while its opposite end is stopped by a plug or a block *g* having a central passageway into one end of which the small end of the body is inserted, and into the opposite end 50 of which, and within the foot is inserted the open end of the shallot. The latter is secured in the plug and the tongue is likewise secured so as to extend over the opening *h* in the side of the shallot, by means of a 55 wedge *i* in the usual manner. The tuning

wire shown is of the usual form and functions in the ordinary manner.

The improvements which I have made, by which I have secured radically new effects in the quality of tone produced by the 60 pipe consist of the following: The shallot is made with greater than ordinary length and is extended below the lower end of the opening *h*, thus forming a pocket *j* below said opening, such pocket of course being 65 closed at the bottom end of the shallot. The top of the body tube is closed or covered by an end wall *k*, thus providing a pocket *l* in said body. In one side of the pocket *l* is a tuning slit *o* adjacent to which is the 70 tuning flap or tongue *p*. The function of this tuning slit and tuning flap is to bring the vibrating period of the column of air in the body *h* into synchronism with the vibrating period of the tongue, the vibrating 75 length of which latter, and by consequence the pitch of the pipe, being controlled by the tuning wire *e*.

I have found that pipes constructed with the novel features above described, that is 80 combining a pocket in the shallot of the pipe below the reed, with a pocket in the top end of the body, simulate exactly the characteristic tone of the French horn.

The drawings here presented to illustrate 85 the foregoing description are not to be taken as limiting the invention to the particular form of reed pipe shown, or as excluding from the scope of my invention modifications in shape, dimensions, and proportions 90 of the pipe, either as to its body and foot or its shallot and tongue, provided the combination hereinafter described is preserved.

Where in the foregoing description and the following claims I have used the words 95 "above", "below", "top", "bottom", or words of similar meanings I have intended such words to refer to the position in which the pipe is shown in the drawing and to that in which it is usually placed, and without any intention of limiting the location or position 100 in which a pipe embodying the invention might be used.

What I claim and desire to secure by Letters Patent is:

1. In a reed pipe, a barrel or resonator having an opening forming a pocket at its upper end, in combination with a shallot having a pocket in its lower end.

2. A reed pipe comprising a barrel hav-

110

ing a pocket in its upper end and a tuning slit in its side, a foot, and a shallot in said foot having a pocket in its lower end with a side opening above such lower end and a tongue extending over the opening.

3. A reed pipe for organs designed to speak with the characteristic tone of the French horn, comprising a body formed with its upper end wholly closed and having a side opening, thereby providing a pocket,

a reed or shallot in line with the bottom end of the body, said shallot being closed at its bottom and having an opening in its side, thereby providing a pocket, a tongue extending over said opening, and the usual foot.

In testimony whereof I have affixed my signature.

ERNEST M. SKINNER.

Copies of this patent may be obtained for five cents each, by addressing the "Commissioner of Patents, Washington, D. C."
